(57) **CLAIM**

The ornamental design for a torch handle, as shown and described.

DESCRIPTION

FIG. 1 is a front perspective view of a torch handle embodying the new design;

FIG. 2 is a rear perspective view thereof;

FIG. 3 is a right-side elevation view thereof;

FIG. 4 is a left-side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken lines shown in the drawings illustrate portions of the torch handle in which the design is embodied that form no part of the claimed design.

1 Claim, 6 Drawing Sheets
